United States Patent Office.

JOHN H. COLDWELL, OF POUGHKEEPSIE, NEW YORK.

Letters Patent No. 76,053, dated March 31, 1868.

IMPROVED BABY-JUMPER.

The Schedule referred to in these Letters Patent and making part of the same.

TO ALL WHOM IT MAY CONCERN:

Be it known that I, JOHN H. COLDWELL, of Poughkeepsie, in the county of Dutchess, and State of New York, have invented a new and improved Baby-Jumper; and I do hereby declare that the following is a full, clear, and exact description thereof, which will enable others skilled in the art to make and use the same, reference being had to the accompanying drawings, forming part of this specification, in which—

Figure 1 represents a side elevation of my improved baby-jumper.

Figure 2 is a plan or top view, partly in section, of the same.

Similar letters of reference indicate corresponding parts.

This invention relates to a new baby-jumper, in which arms projecting from the straight seat-bar are pivoted to arms projecting from the base, the arms on the seat-bar being adjustable, so that the fulcrum can be brought nearer to or farther from the seat, and so that thereby the apparatus can be adapted for more or less heavy children.

The front end of the seat-bar is, by means of a spiral spring, connected with the front part of the base, the tension of said spring being adjustable by means of a screw, to which one end of the spring is secured. The railing around the seat is provided with a swinging or detachable gate, so that it can be opened, whenever desired, to facilitate the ingress or egress of the child.

A, in the drawing, represents the base of my improved baby-jumper, said base consisting of two or more bars, or of a plate of suitable size and shape. B B are two or more lugs or ears, projecting from the front part of the base, said lugs being transversely in line with each other. C is a straight seat-bar, to the rear end of which the seat D is secured. To the under side of the seat-bar is secured, by means of a bolt, a, or otherwise, a slotted plate, E, from which two or more lugs, b b, project downward, said lugs being, by means of one or more pins, c, pivoted to the lugs B, as shown. The front end of the bar C is, by means of a spring, F, connected with the front part of the base, A, the upper end of the spring being fastened to a screw-bolt, d, which passes through the bar C, as shown, and by means of which the tension of the spring can be regulated.

By adjusting the bar C on the plate E, the distance from the seat to the plate E can be lengthened or shortened at will, and thereby the leverage can be adjusted for heavier or lighter children.

Instead of having the plate E slotted, the seat-bar C may be slotted, or either of them may be so arranged that the bolt a can be longitudinally adjusted in the same.

The seat D is surrounded with a railing, G, as usual, a portion, H, of which is hinged either to the remaining stationary part of the railing, or by means of a post or upright, I; to the seat-bar C, as shown, or is otherwise made so that it can be swung open or detached.

In fig. 1 the railing is shown closed, and in fig. 2, opened. When closed, the detachable part H is fastened to the main part, G, of the railing by suitable locking-devices.

Having thus described my invention, I claim as new, and desire to secure by Letters Patent—

1. Making the seat-bar of a baby-jumper longitudinally adjustable on its fulcrum, substantially as herein shown and described.
2. Making a portion, H, of the railing around the seat of a baby-jumper detachable, or so that it can swing open, substantially as and for the purpose herein shown and described.
3. The arrangement and combination with each other of the base, A, ears B, seat-bar C, adjustable plate E, lugs b, spring F, and screw d, all made and operating substantially as herein shown and described.

JOHN H. COLDWELL.
